Specification of Letters Patent.

Patented Jan. 18, 1916.

Application filed April 24, 1913. Serial No. 763,448.

To all whom it may concern:

Be it known that I, LUIGI CEREBOTANI, a citizen of Italy, residing at Munich, Germany, have invented a new and useful Printing-Telegraph, of which the following is a specification.

The present invention relates to the following three kinds of electrical type-printing telegraphic apparatus: The first kind 10 employ type-wheels, which are not only moved isochronously, but also synchronously at both end-stations, which movement is not controlled by current impulses, (but, for instance, by clockwork) the impression of a 15 type being operated by a line-current, which is closed by the depressed key, when at both end-stations the type runs past the paper band. The second kind makes use of an intermittent rotation of the type-wheels at 20 both end-stations, such rotation taking place under the influence of a current, which liberates certain escapement wheels. This movement is operated by once switching in a special line-current at the transmitting 25 station, before the telegraphic printing commences. On a key then being depressed, the movement stops, as soon as the corresponding type has reached the paper band (an impression being at the same time made by the 30 said type), on the key being released, however, the intermittent feed motion recommences forthwith. The third kind also makes use of an intermittent motion of the 35 type-wheels, but in such a manner that everything remains at rest, so long as none of the keys are depressed, and that by depressing any key the type-wheel is caused to go on rotating until the desired corresponding type is brought into its operative 40 position. At this instant an impression of the type is made, an uncoupling takes place and the type-wheels snap back into their initial position. A new movement only ensues, 45 when a key is again depressed. The main thing with all these kinds of type-printing telegraphic apparatus is the obtaining of consonance in the proceedings at the two end-stations. With the first kind of apparatus the establishment of consonance in the 50 position of the two type-wheels is in general effected by transmitting from one end-station to the other a certain character, the machines running the while uninterruptedly, while the operator at the other end-station 55 sets his clockwork and type-wheel in corre-

spondence therewith. With the other kinds of apparatus consonance is established by the type-wheels automatically and simultaneously attaining the initial position and stopping there, this occurring in the second kind after the completion of a certain number of rotatory motions, and in the third kind, as above explained, immediately after an impression is obtained. Just as with these last-named type-printing telegraphic apparatus the mode of the intermittent feed motion of the type-wheel is simple and sure, the obtaining of the consonance in question is very much more reliable, than is the case with the apparatus previously mentioned. 60 It is, on the other hand, a drawback, that the twofold action, viz. the uncoupling and the snapping back of the type-wheel into its initial position for each letter makes a not inconsiderable mechanical demand on the apparatus, whereby the simplicity, stability and durability of the apparatus suffers, while a certain loss of time is unavoidable, as slight as it may be. These drawbacks are 65 obviated by the present invention. 70

The new mode of operation is derived from the third kind alluded to, it would, however, be easily adaptable for the other two kinds, only unimportant modifications in the form of construction being required. 75 The peculiarity of the new arrangement consists in the following: After an impression is made, the type-wheel continues to rotate, the uncoupling, the snapping back of the type-wheel into its initial position and the 80 re-coupling taking place at both end-stations either on any key at either end-station remaining depressed for some time or on a special key or the like being depressed at either end-station, as soon as this should appear desirable. In general this is carried out by no longer placing the part, which has to bring about the reestablishment of the 85 initial position, in connection with the armature, which causes the making of the impression, but by rendering the said part dependent on the acting of a special magnet, which magnet acts, only when, as was just indicated, a special key is depressed at one 90 of the two end-stations. 95

In the annexed drawing: Figures 1 and 2 give a diagrammatic representation in two positions of a type-printing telegraphic apparatus, according to the invention, Fig. 3 shows a detail of the uncoupling mechanism, 100 105 110

Fig. 4 shows the printing magnet, Figs. 5 to 7 represent the mechanism for reestablishing the initial positions of the type wheel (Figs. 3 to 7 being drawn to an enlarged scale), Figs. 8 and 9 show diagrammatically two different ways of connecting up the apparatus.

In the following Figs. 1 to 7 shall be first explained. A shaft 8 is journaled rotatably and non-displaceably and carries a disk 13. A sleeve 7 is journaled rotatably and displaceably on the shaft 8. The said sleeve carries a disk fitted with a projection 9 and a pin 12. The pin 12 has the same distance from the axis of the shaft 8 as a slot in the disk 13 and the projecting piece 9 is displaced by 90° with regard to the pin 12. With the sleeve 7 positioned as shown in Fig. 2, in which it is in its right-hand end position, the projecting piece 9 reaches in between a spring-controlled projection 11 and a stop 10, while with the sleeve positioned as in Fig. 1, in which it is in its left-hand end position, the projecting piece 9 is out of engagement with the parts 10 and 11. There is further fixed on the sleeve 7 a disk 3, which has an indenture at the bottom of its periphery, and a disk 22, a toothed wheel 18 and a type-wheel 5. A rod 2 is pivoted at 14. An electromagnet 15, on being energized, draws the rod across to the left, while a spring serves for returning it to the right again. A printing magnet 6 is provided for pressing the paper tape by means of a roller 1 against the type-wheel 5. A magnet 30 and an armature 32 serve for causing a step by step rotation of the shaft 8. The toothed wheel 18 engages with the teeth of a broad rack 17, which is displaceable on a bar 16 and is controlled by a spring 19. At one of its ends and on a portion of its breadth the rack is without teeth. At one side of the bar 16 a spring-controlled locking lever is pivotally mounted, which is provided at the side facing the rack with a catch 20 and at the side facing the disk 22 with a projection 21.

With the sleeve in the position shown in Fig. 1 it is coupled by means of the pin 12 with the disk 13 and consequently with the shaft 8. When, during the working of the apparatus, the sleeve 7 carried around by the step by step motion of the shaft 8 has made a complete revolution in the direction opposite to the arrow shown in Fig. 7, the toothed wheel 18 has brought the rack in the direction of the arrow shown in Fig. 5 from the position given in Fig. 5 into that given in Fig. 6 and has by this means put the spring 19 in tension. The catch 20 then slips in behind the rack and prevents it snapping back again. At the termination of the movement of the rack the toothless part of the same has come below the toothed wheel, so that the latter along with the

type-wheel can make further rotations, without the spring being further tensioned. Should it be desired to return the type-wheel, after a certain number of impressions have been made, into its initial position, this is accomplished in the following manner. On the electromagnet 15 being energized by a special current, which is more particularly explained below, it draws the rod 2, which is normally kept to the right under the action of a controlling spring, to the left, the end of the rod passing under the disk 3, so that the rod takes up the position indicated by full lines in Fig. 2. On the current energizing the electromagnet 15 ceasing, the controlling spring draws the rod 2 toward the right again. On its return the rod-end rests against the disk 3 and pushes the sleeve along with the parts fixed to it to the right along the shaft 8, so that the pin 12 is withdrawn from the slot in the disk 13 and by this means the sleeve 7 and with it the type-wheel 5 is uncoupled from the shaft 8. By the displacement of the sleeve the toothed wheel 18 is brought into mesh with the teeth of the rack 17, while at the same time the disk 22 presses against the projection 21 of the locking lever and thereby causes the catch 20, to set the rack 17 free. Through the tension of the spring 19 the rack is caused to snap back into the position shown in Fig. 5. During this movement the rack rotates the toothed wheel 18 and along with it the sleeve 7 in the opposite sense to its former direction of rotation. Finally, during the rotation of the sleeve the projecting piece 9 comes in contact with the spring controlled projection 11, is retarded by the latter, strikes the stop 10 and is prevented by the latter from rotating farther. In this position the type-wheel has again reached its initial position. The rod 2 now stands exactly in front of the indenture of the disk 3. The disk 3 and with it the sleeve 7 is consequently no longer prevented from sliding along the shaft 8 to the left. This displacement is effected through the action of a spring not shown in the drawing, the pin 12 engages with the slot in the disk 13 and the coupling between the sleeve 7 and the shaft 8 is thus restored. By the displacement of the sleeve to the left the disk 22 has also moved away from the projection 21, so that the catch 20 is again able to slip behind the rack 17, when the latter has again reached, after a certain number of steps of the type-wheel, the position shown in Fig. 6.

A further innovation, which however does not belong to the essence of the invention, is in so far provided in the present arrangement, as the most frequently occurring types (numbering about 8 to 10) are fitted twice to the type-wheel at equal distances. Furthermore that part, which gives no impres-

sion and has only to cause the displacement of the paper for the necessary spaces, occurs frequently. The object of this arrangement is, that these types may be reached during the intermittent feed motion in the shortest possible time, without having recourse to one of those well-known, to say the least troublesome arrangements, which bring about the same result by effecting a displacement of the type-wheel.

The operation of the device shall now be explained with reference to the circuit diagrams given as examples in Figs. 8 and 9.

In Fig. 8 the uncoupling is effected by the somewhat prolonged depression of any key, in Fig. 9, on the other hand, by the employment of a special current and by means of polarized relays. The fixed disks 24 and 25, which are composed of non-conducting materials, correspond to those bearing the same numbers in Fig. 1. The metal contact pieces 26 on disk 24 are insulated from each other and are each in metallic contact with one of the keys 27. The contact pieces 28 on the disk 25 are connected together and come in contact with the shaft 8, one after another, by means of a contact-maker 29 fixed on the shaft 8. A contact-maker 31 is fixed on the sleeve 7 and, on the latter rotating, connects the sleeve with the contact pieces 26 successively. The contact makers 29 and 31 are so positioned relatively to one another that, when the contact maker 29 lies on one of the contact pieces 28, the contact maker 31 lies between two of the contact pieces 26. A circuit closer 38 is so positioned that, on the upper end of the part 32 moving to the left, contact is established between 38 and 32. When in the arrangement according to Fig. 8 any key 27 is depressed, a current is caused to flow from battery 33, over 8, 29, a contact piece 28, 34, 35, magnet 30, by way of line 36 to the other end-station, there over magnet 30, 35, 37, and back again by the earth to battery 33. This current automatically flows and is interrupted repeatedly through the rotation of 29 over 28, until 31 has reached the contact piece 26, which is connected with the depressed key. The current now no longer interrupts itself, as it finds between 8 and 35 a path over 31, 26 and the depressed key 27. Now in consequence of the uninterrupted current at the circuit-closer 38 a local circuit is closed (39, 38, 32, magnet 6, 40, 39), which causes an impression to be taken of the type set for. On the depressed key being released the type-wheel will rotate forward by only half a step. On a second key being depressed a further intermittent feed motion commences and continues until the contact piece 26 corresponding to this key is reached by 31, and so on. On the key remaining depressed for some time, the above described procedure of the

reestablishment of the initial position will be inaugurated at both end-stations. This is brought about in the following manner: The electromagnet 15 is constituted in the well-known manner, that a certain period elapses before it acts, and is connected up in a circuit (deriving its current either as shown in Fig. 8 from the same current-source as serves for the energizing of magnet 6 or from its own current-source), which circuit is also closed at the circuit closing piece 38 and remains closed as long as the line-current continues. When, therefore, it is desired simultaneously with the acting of 6 to cause 15 to act, and thus to reestablish the initial position, the key must remain depressed for some time, by which means, besides the line-circuit from 33 and the local circuit 39, 6, 32, 39, the other local circuit 39, 15, 32, 38, 39, remains closed for as long as the key remains depressed. This is done in order to make sure that the same is happening at the other end-station, for a short time after the acting of the magnet 15 has been perceived. On the key rising, these circuits are opened and at both end-stations the initial position is at once reestablished, as was explained.

The connection according to Fig. 9 is more complicated, but will be more suitable in most cases. In this case there are used in addition a second oppositely directed line-current source 41, two polarized relays 42 and 43 and a key 44, which latter has the purpose of switching in 41 and at the same time switching off the earth connection. The relation of the printing magnet 6 to the intermittent feed motion magnet 30 remains unaltered, as was explained in connection with Fig. 8. The uncoupling magnet 15 is, on the other hand, solely dependent on the relay 43, *i. e.* it only acts, when 43 has acted. Magnet 30 as well is controlled by a relay 42 and is connected up in a local circuit. The two delays 42 and 43 are connected in the long distance line in series and with reversed polarity. While one of them, 42, acts only when a positive current is sent out from 33, and ceases to act when a negative current is sent out from 41, the other one, 43, will act with the latter and cease to act with the former current. Hence, when any key 27 is depressed and by this means a current from 33 flows over 8, 29, 28, 34, 35, 45, relay 42, relay 43, by way of line 36 to the other end-station, there over relay 43, relay 42, 45, 35, 37, and back again by the earth to 33, then 42 alone acts at both end-stations and switches in the local circuit 30, 46, 47, 48, 30. Consequently the current from 33 interrupts itself at the disk 25, so that 30 again becomes currentless, which again results in a closing of the circuit from 33, and so on. The further action of the sleeve with its parts is the same as explained

in the case of Fig. 8. Should it appear desirable, after impressions have been made of a series of types, for the type-wheel to spring back into its initial position at both end-stations, it is only necessary to depress the key 44 at one of the end-stations. By this means there results a current from the battery 41 having the following course: 41, 49, 45, relay 42, relay 43, by way of the line 10 36 to the other end-station, there over relay 43, relay 42, 45, 35, 37, and back again by the earth to 41. On this current flowing there acts, as indicated above, at both end-stations only the relay 43, so that now the 15 circuit containing 15 is closed, viz., the circuit 39, magnet 15, 50, 51, 39. The reestablishment of the initial position at both end-stations is thus again inaugurated.

I claim:

20 1. In an electrical type-printing telegraph a transmitting apparatus comprising a set of keys, only one rotatable type-wheel and means for causing the depression of the said keys to result in the making of impressions 25 of the said types, means for causing the type-wheel to be brought back from any position into its initial position and a special key for operating the said latter means and receiving apparatus comprising similar parts 30 to those of the said transmitting apparatus, adapted to coat simultaneously with those parts.

2. In an electrical type-printing telegraph a transmitting apparatus comprising a set of 35 keys, a rotatable shaft, a type-wheel mounted on the said shaft, means whereby the type-wheel is adapted to be coupled with the said shaft and other means for causing the depression of the said keys to result in the 40 making of impressions of the said types, a special key, a source of current controlled by the said key, an electromagnet capable of being energized by the said current and adapted to uncouple the type-wheel from its 45 shaft, a spring adapted to be put in tension by the rotatory motion of the said type-wheel and quickly to return the type-wheel from any position into its initial position and receiving apparatus comprising similar parts 50 to those of the said transmitting apparatus, adapted to coat simultaneously with those parts.

3. In an electrical type-printing telegraph a transmitting apparatus comprising a set of 55 keys, a rotatable shaft, a type-wheel mounted on the said shaft, means whereby the type-wheel is adapted to be coupled with the said shaft and other means for causing the depression of the said keys to result in the 60 making of impressions of the said types, a special key, a source of current controlled by the said key, an electromagnet capable of being energized by the said current and adapted to uncouple the type-wheel from its 65 shaft, a spring adapted to be put in ten-

sion by the rotatory motion of the said type-wheel and quickly to return the type-wheel from any position into its initial position, a spring-controlled stop adapted to prevent the type-wheel from recoiling at the end of 70 its quick return and receiving apparatus comprising similar parts to those of the said transmitting apparatus adapted to coat simultaneously with those parts.

4. In an electrical type-printing telegraph 75 a transmitting apparatus comprising a set of keys, a rotatable shaft, a sleeve rotatable and slidable on this shaft, means whereby the sleeve is adapted to be coupled with the said shaft, a type-wheel fixed on the said 80 sleeve, a toothed wheel fixed on the said sleeve, a longitudinally slidable and spring-controlled rack adapted to mesh with the said toothed wheel and having a portion of some of its teeth missing, means for stopping the motion of the said rack, means for causing the depression of the said keys to result in the making of impressions of the 85 said types, a special key, a source of current controlled by the said key, an electromagnet 90 capable of being energized by the said current and adapted to uncouple the sleeve from its shaft, a spring adapted to be put in tension by the rotatory motion of the said type-wheel and quickly to return the 95 type-wheel from any position into its initial position, a spring-controlled stop adapted to prevent the type-wheel from recoiling at the end of its quick return and receiving apparatus comprising similar parts to those of the 100 said transmitting apparatus, adapted to coat simultaneously with those parts.

5. In an electrical type-printing telegraph 105 a transmitting apparatus comprising a set of keys, a rotatable shaft, a sleeve rotatable and slidable on this shaft, means whereby the sleeve is adapted to be coupled with the said shaft, a type-wheel fixed on the said sleeve, a toothed wheel fixed on the said 110 sleeve, a longitudinally slidable and spring-controlled rack adapted to mesh with the said toothed wheel and having a portion of some of its teeth missing, means for stopping the motion of the said rack, means for causing the depression of the said keys to result in the making of impressions of the 115 said types, a special key, a source of current controlled by the said key, an electromagnet capable of being energized by the said current and adapted to uncouple the sleeve 120 from its shaft, a spring adapted to be put in tension by the rotatory motion of the said type-wheel and quickly to return the type-wheel from any position into its initial position, a line-battery adapted to be put in 125 circuit by the said special key and to cause a current to flow, a relay adapted to act on this current flowing and to close the circuit containing the said electromagnet, a second relay connected up with the first relay, but 130

- operated with reversed polarity, and adapted to act, on any key of the said set of keys being depressed, a second battery adapted to be put in circuit in place of the said line-battery and to cause a current to flow in the opposite direction to the current from the said line-battery and to cause the said second relay to act, and receiving apparatus comprising similar parts to those of the said transmitting apparatus, adapted to coact simultaneously with those parts.
5. In an electrical type-printing telegraph a transmitting apparatus, comprising a set of keys, a rotatable type wheel and means for causing the depression of the said keys
- 10
- 15
- to result in the making of impressions of the said types, means for causing the type-wheel to be brought back from any position into its initial position and means adapted to operate the said latter means when any key is depressed for a somewhat longer time and receiving apparatus comprising similar parts to those of the said transmitting apparatus, adapted to coact simultaneously with those parts.
